(57) **CLAIM**

I claim the ornamental design for a vehicle oil pan drain plug, substantially as shown and described.

DESCRIPTION

FIG. 1 is a front perspective view of the first embodiment of the invention.

FIG. 2 is a top plan view of the invention in FIG. 1.

FIG. 3 is a bottom plan view of the invention in FIG. 1.

FIG. 4 is a front view of the invention in FIG. 1.

FIG. 5 is a right view of the invention in FIG. 1.

FIG. 6 is a rear view of the invention in FIG. 1.

FIG. 7 is a left view of the invention in FIG. 1.

FIG. 8 is a cross-sectional view of FIG. 1 along line 8-8.

FIG. 9 is a front perspective view of a second embodiment of the invention.

FIG. 10 is a top plan view of the invention in FIG. 9.

FIG. 11 is a bottom plan view of the invention in FIG. 9.

FIG. 12 is a front view of the invention in FIG. 9.

FIG. 13 is a right view of the invention in FIG. 9.

FIG. 14 is a rear side view of the invention in FIG. 9.

FIG. 15 is a left view of the invention in FIG. 9; and,

FIG. 16 is a cross-sectional perspective view of FIG. 9 along line 16-16.

The broken lines represent portions of the article and form no part of the claimed design.
